HIGH VOLTAGE SWITCH

William R. Huttinger, Lansdowne, Pa.

Application February 1, 1941, Serial No. 377,031

4 Claims. (Cl. 200—48)

This invention relates to high voltage switches and has for an important object thereof the provision of a switch blade having clamping jaws for forcibly engaging the coacting arms of a stationary contact together with means for locking the jaws in their gripping position, the locking means being so constructed that it may be readily released by a primary movement of the actuating apparatus controlling movement of the movable blade.

Another object of the invention is to provide a switch mechanism of this character in which the operating parts may be housed to the greatest possible extent, thereby preventing failure in operation or difficult manipulation as a result of collection of ice about the various switch parts.

Still another object of the invention is the provision of a construction of this character which will be very simple and durable in construction and which may be very readily manufactured.

These and other objects I attain by the construction shown in the accompanying drawings wherein, for the purpose of illustration, I have shown a preferred embodiment of my invention and wherein:

Fig. 1 is a plan view partially in section of a switch unit constructed in accordance with my invention;

Fig. 2 is a side elevation partially in section of the switch;

Fig. 3 is a detail sectional view on line 3—3 of Fig. 1, the switch parts being shown in a released position;

Fig. 4 is a similar section showing the switch parts in the locked position;

Fig. 5 is a section on line 5—5 of Fig. 4;

Fig. 6 is a side elevation of the operating portion of the switch with the switch in closed position;

Fig. 7 is a similar view with the switch in open position;

Fig. 8 is a horizontal sectional view through the switch head taken on line 8—8 of Fig. 9;

Fig. 9 is a vertical sectional view through the switch head;

Fig. 10 is a horizontal sectional view through a modified form of switch head;

Fig. 11 is a vertical sectional view through the switch head shown in Fig. 10;

Fig. 12 is a section on line 12—12 of Fig. 10; and

Fig. 13 is a sectional view through the counter-balance employed for balancing the weight of the switch arm.

Referring now more particularly to the drawings, the numeral 10 generally designates an insulator mounting a rotatable shaft 11. Adjacent insulator 10 is a second insulator 12 having mounted thereon a supporting frame-work 13 one end of which is secured to insulator 10 and is constructed as at 14 for attachment of a bus, and apertured for the passage of shaft 11 therethrough. The opposite end of supporting frame 13 has pivoted thereto, as at 15, a switch blade 16. This switch blade comprises a housing member 17 with which the pivot 15 is directly engaged, a switch head 18 adapted to engage with switch contacts 19 mounted upon a suitable insulator 20, and a tube 21 connecting housing 17 and head 18 and of such length as to provide for proper spacing of the head and housing. Insulator 20 has a blade base 22 upon which the blades 19 of a fixed contact are mounted, said base mounting a cushioning bumper 23 limiting the movement of the switch head into the closed position, and being likewise adapted as at 24 for the attachment thereto of a bus.

The switch head of Figures 1 to 9, shown more particularly in Figures 8 and 9, comprises a hollow casing 25 having a fixed jaw 26 adapted for coaction with one of the blades 19 and a movable jaw 27. The movable jaw comprises one arm of a lever pivoted at 28, said lever having its second arm 29 disposed within the casing 25. Arm 29 is provided with a longitudinally-extending slot having obtusely angularly related portions 30 and 31. Within suitable guides 32 formed on the casing walls, a cross-head 33 is mounted upon rollers 34 and this cross-head has a further roller engaging in the slot of arm 29. It will be obvious that if the cross-head 33 is moved to the right from the position illustrated in Figures 8 and 9, the cross-head will by its transposition from one to the other of the angularly related portions of the slot cause the lever to rotate about its pivot, thereby shifting the movable jaw 27 to cause it to disengage from the associated contact 19. It will be noted that portion 30 of the slot is relatively elongated so that a substantial movement of the cross-head must take place before any movement of the movable jaw is effected. An operating rod 35 is connected to cross-head 33 and actuated in a manner now to be described.

50 Rotatably mounted in the upper portion of the housing 17 is a shaft 36 which is provided within the housing with an arm 37 to which the inner end of rod 35 is pivoted as at 38. The pivot 15 comprises a stationary shaft about which housing 17 is rotatable in suitable bearings 39. Rotatably

mounted on this shaft is a toggle link 40 the free end of which is link-connected by links 41 to pivot 38. A spring 42 surrounding the shaft constantly urges link 40 in the direction of the arrow A of Figures 3 and 4, thus tending to straighten the toggle.

Rotatably mounted upon pivot shaft 15 is a stop arm 43 having at its outer end an adjustable stop 44. While arm 43 may rotate freely in the direction of the arrow B, Figure 3, its movement in the opposite direction is limited by coacting shoulders 45, formed on the hub of arm 43, and 46, formed on a collar 47 fixed to shaft 15. These shoulders engage during movement of the switch arm 16 to the "closed" position, positively limiting movement of arm 43 at the position shown in Figure 3. As casing 17 rotates about its pivot, however, arm 43 is free to remain at the position shown in Figure 3 and will only be shifted at the time when the casing wall and, more particularly, the removable cover plate 48 through which adjustment of stop 44 is effected, comes in contact with the stop. The position of stop 44 is such, as more clearly shown in Figure 4, that when the switch is in its closed position an extension of the pivot pin 49 connecting link 40 with links 41 engages this pivot pin and maintains the toggle in its broken position, that is to say, a position where pressure applied through pivot 38 will tend to fold it against the action of spring 42 to the position shown in Figure 3. During rotation of housing 17 about its pivot, from the position shown in Figures 3 and 4 to the elevated or open position of the switch as illustrated in Figure 7, stop 44 becomes ineffective and toggle links 40, 41 are moved by spring 42 to their locking position, as illustrated in Figure 7. In this position they will remain until during movement from the position shown in Figure 7 toward that illustrated in Figures 3 and 4 they have arrived at the position shown in Figure 4. At this time the shoulders 45 and 46 are in engagement and the movement of arm 43 is arrested and the stop has sufficiently engaged with the pivot 49 connecting the toggle links to break the toggle. At the same time, the switch head has its jaws in opposition to and in proper position for engagement with the blades 19 of the stationary contact of the switch. At this time further rotation of the shaft in the direction of the arrow C will break the toggle against the action of spring 42 causing the jaws of the switch head to forcibly engage the contacts 19.

Externally of the housing 17 shaft 36 is equipped with a pair of arms 50 between which a rotatable element 51 is supported. This rotatable element is engaged by one end of a link 52 the opposite end of which is universally connected at 53 with an arm 54 secured to the upper end of shaft 11. Between the housing 17 and that end of the supporting framework 13 which is mounted on insulating post 10 a counter-balancing mechanism 55 is arranged, this mechanism being so constructed that it will resist the falling weight of switch arm 16 and, accordingly, assist in elevating the same. As at present shown, this mechanism comprises a housing 56 into one end of which extends an arm 57 pivotally connected to the frame or supporting structure 13 adjacent shaft 11 as at 58. This arm extends into the casing 56 and has at its free end a flange 57 forming a seat for one end of a spring 60. The casing 56 is pivotally connected to the housing 17 as at 51 and has arranged interiorly thereof a fixed disc 62 forming a seat for the opposite end of 75

spring 60. As the switch arm 16 moves towards its "closed" position, spring 60 is compressed and in its compression assists in checking the movement of the arm. The compressed spring during movement of the arm from the horizontal closed position to the vertical open position will, of course, assist in elevating the same.

In considering the operation of the mechanism, let it be supposed that it is disposed in the position shown in Figures 1, 2, 3 and 6, i. e., in the closed position, and that it is desired to open the switch. The jaws of switch head 18 are at this time locked against the arms of stationary contact 19 by reason of the fact that link 52 and arm 54 of shaft 11 constitute a toggle mechanism which, in the fully closed position of the jaws of switch head 18, has its central pivot, included in the universal connection 53, arranged beyond a plane including the vertical pivot 63 of link 52 to arms 50 and the axis of the shaft 11. Therefore, any force acting to elevate head 18 must shift the pivot of the toggle mechanism in a direction in opposition to the arrow E, which shift is prevented by reason of the fact that the cross-head 33 is then at the inner limit of its movement and/or by engagement of a portion of the operating mechanism 64 by a fixed stop 65. Consequently, shaft 11 can only be rotated in the direction of arrow E and rotation in this direction first breaks the toggle consisting of the link 52 and arm 54 and then rotates shaft 36 in the direction indicated by arrow C' of Figure 3. Rotation of shaft 36 in this direction causes rod 35 to shift to the outer end 31 of the slot of lever arm 29 with the result that the movable jaw 27 separates from the fixed jaw 26 freeing the outer end of the switch arm 16 for movement. When this portion of the motion is completed, stop 44 will positively limit movement of the central pivot 49 of the toggle mechanism 40, 41 and thereafter strain placed upon link 52 through arm 54 will act to cause swinging of the switch arm 16 about pivot 15. As the switch arm elevates, the shoulders 45 and 46 disengage permitting lug stop 44 to recede under the pressure placed thereagainst by pivot 49 through the action of spring 42. Spring 42 will move the toggle mechanism 40, 41 to a locking position at which it is checked by the coaction of stops 66 and 67 carried respectively by links 40 and 41. This toggle mechanism will, therefore, during closing movement of the switch act as a lock preventing rotation of shaft 36 until the switch arm is moved from the position shown in Figure 7 to the position shown in Figure 4, at which time stop 44 by its engagement with pin 49 will break the toggle 40, 41 so that continued motion of the link 52 in a direction opposed to the arrow F of Figure 4 will collapse the toggle against the action of spring 42 to the position shown in Figure 3 thereby permitting rotation of shaft 36.

It has been hereinbefore pointed out that at the time when the mechanism moving toward its closed position reaches the position illustrated in Figure 4, jaws 26 and 27 are arranged in opposition to the switch arms 19 and are in readiness to clamp thereagainst; the final portion of the closing movement of operating mechanism 64 will of course serve to lock the toggle mechanism 52, 54 and thus lock the jaws 26, 27 against the arms of contact 19.

Utilizing a mechanism of this character, it is, of course, possible to widely vary the construction of the head 18 and the method of its coaction with the arms of the contact 19. In the

form of head illustrated in Figures 10, 11, and 12, the head 68 has pivotally mounted therein a pair of levers 69 opposed faces of which have correspondingly but oppositely angled angularly related faces 70. The stationary contact 19 comprises a pair of relatively rigid horns 72 between which the head engages in its closing movement. Levers 69 are each provided, on the arms thereof bearing surfaces 70, with a lug 73 adapted to extend through an opening 74 in the casing wall. The cross-head 75 is guided from casing ribs 76 as in the construction hereinbefore described and bears rollers 77 for engagement with adjacent faces of the levers 69. When the cross-head is positioned to engage the surfaces 70, the lugs 73 are projected through the openings 74 to engage the contacts or horns 72. When, however, the cross-head is shifted to engage the surfaces 71 of levers 69, these lugs are drawn into the casing freeing the head 68 for movement. In a construction of this character the utilization of a fixed stop associated with the operating mechanism is advisable.

It will be obvious that a mechanism of the type just described is relatively simple in its construction, operation, and adjustment, and may be so housed that there is little danger of interference with its operation through the collection of foreign matter on the contacts. It will also be obvious that the specific construction illustrated is capable of considerable modification without departing from the spirit of my invention and I, accordingly, do not wish to be understood as limiting myself thereto except as hereinafter claimed.

I claim:

1. In a switch of the type described, a stationary contact, a switch arm pivoted at one end and having at its free end a contact head for engagement with said stationary contact, relatively movable members carried by said contact head for coaction with said fixed contact, said members having engaging and releasing positions, a single actuating means for shifting said switch arm to engage and disengage the contact head and said stationary contact, a reciprocable member having camming engagement with said movable members to positively shift the same to contact-engaging and disengaging positions, means including a toggle mechanism acting in one position thereto to positively lock the reciprocable member against movement when said head is out of alignment with the stationary contact, a spring normally holding the toggle in said position, and a stop to engage and to break the toggle against the action of said spring and thereby permit movement of the reciprocable member when the head is in alignment with the stationary contact.

2. In a switch of the type described, a stationary contact, a switch arm pivoted at one end and having at its free end a contact head for engagement with said stationary contact, said contact head comprising a pair of members for

coaction with said contact, said members being centrally pivoted to permit relative movement of corresponding ends thereof into and out of clamping engagement with said stationary contact, a rod movable longitudinally of the switch arm, said member having angularly related cam faces at opposite sides of the pivots thereof with which said rod coacts, the engagement of the rod with said cam faces positively shifting said members about their pivots into and out of clamping positions and means preventing operation of said rod when the contact head is out of engagement with the stationary contact.

3. In a switch of the type described, a stationary contact, a switch arm pivoted at one end and having at its free end a contact head for engagement with said stationary contact, said contact head comprising a pair of members for coaction with said contact at least one of which is pivoted to permit relative movement of the members into and out of clamping engagement with said stationary contact, a rod movable longitudinally of the switch arm, said pivoted member having angularly related cam faces with which said rod coacts, the engagement of the rod with said cam faces positively shifting said member about its pivot into and out of clamping position, an oscillatable arm for shifting said rod, a toggle mechanism acting in one position thereof to positively lock the rod against movement when said head is out of alignment with the stationary contact, a spring normally holding the toggle in said position and a stop to engage and break the toggle against the action of said spring and thereby permit movement of the rod when the head is in alignment with the stationary contact.

4. In a switch of the type described, a stationary contact, a switch arm pivoted at one end and having at its free end a contact head for engagement with said stationary contact, said contact head comprising a pair of members for coaction with said contact, said members being centrally pivoted to permit relative movement of corresponding ends thereof into and out of clamping engagement with said stationary contact, a rod movable longitudinally of the switch arm, said member having angularly related cam faces at opposite sides of the pivots thereof with which said rod coacts, the engagement of the rod with said cam faces positively shifting said members about their pivots into and out of clamping positions, an oscillatable arm for shifting said rod, a toggle mechanism acting in one position thereof to positively lock the rod against movement when said head is out of alignment with the stationary contact, a spring normally holding the toggle in said position and a stop to engage and break the toggle against the action of said spring and thereby permit movement of the rod when the head is in alignment with the stationary contact.

WILLIAM R. HUTTINGER.
